UNITED STATES PATENT OFFICE.

LESLIE M. N. WISE, OF MCKEESPORT, PENNSYLVANIA.

GENERATOR.

1,315,268.

Specification of Letters Patent

Patented Sept. 9, 1919.

Application filed October 26, 1918. Serial No. 259,831.

To all whom it may concern:

Be it known that I, LESLIE M. N. WISE, a citizen of the United States, and a resident of McKeesport, in the county of Allegheny, 5 and State of Pennsylvania, have invented a certain new and useful Improvement in Generators, of which the following is a specification.

My invention relates to improvements in 10 gas generators, and it consists in the construction, combination and arrangement of parts as herein described and claimed.

An object of my invention is to provide a 15 generator, adapted more particularly for generating gas under extremely high pressures, one of the foremost principles of the invention residing in the means for equalizing the gas pressures in the fluid and chemical containers.

20 Other objects and advantages will appear in the following specification, reference being had to the accompanying drawing in which—

Figure 1 is a vertical section of the improved gas generator, and

Fig. 2 is a plan view of the coupling.

The gas generator comprises a chemical container 1 and a fluid container 2. Both of these are provided with screw threads 3 and 30 4 respectively at the adjacent ends, and by this means are joined together through the medium of a coupling 5 which also acts as a partition between the two containers.

Both containers have annular raised portions 6 which in practice are knurled, to facilitate gripping them in unscrewing them from the coupling. The coupling 5 has a central dome 7 with a duct 8 and lateral opening 9. The passage of the fluid from 40 the container 2 through the duct 8, is controlled by the valve 10.

A boss 11 provides the bearing or mounting for the valve 10. A gland 12 includes a packing 12^a which prevents the escape of 45 gas out of the bore in which the valve operates. A gas equalizing pipe 13 is fixed in the coupling 5 as illustrated, and terminates near the roof of the container 2.

In practice the upper end of the pipe 13 50 stands well above the level of the fluid. The purpose of this pipe, is to convey gas from the container 1 to the top of the fluid container 2, thus filling both of these chambers with gas at an equal pressure. The dropping 55 of the fluid at the duct 8 will thus continue without interruption. This generator

is intended for the generation of gas under extremely high pressures, as has already been indicated. Obviously a rise of gas pressure in the container 1 to any considerable extent, would at once cause the fluid to cease flowing or dropping out of the duct 8. The equalizer pipe 13 prevents this in the manner already stated.

Gas is conducted out of the container 2 by 65 a connection 14. The bore of the connection is somewhat flared at the exposed end, to facilitate the filling of the container 2 with fluid, when the union 15 is removed for the purpose. The pipe 16 secured to the connection 14 by the union, leads to any suitable 70 gas container or any desired device such as a filterer.

It has been demonstrated in practice, that the gas pressure inside of the generator becomes so great that the turning of the union 15 is almost impossible, by reason of the tension on the threads. The pet cock 17 at one side of the container 2, enables the relief of the gas pressure on the inside so that 80 the union 15 may be turned.

While the construction and arrangement of the generator is that of a generally preferred form, obviously modifications and changes may be made without departing 85 from the spirit of the invention or the scope of the claims.

I claim:—

1. In a gas generator, a gas receiving container, means for conducting away the 90 gas including pipe connections with a union, and means including a pet cock for preliminarily relieving the pressure of gas in the container to enable the unscrewing of the union for the removal of the pipe connection.

2. A gas generator, comprising a chemical container, a fluid container, means for periodically dropping the fluid upon a chemical in the chemical container to generate gas, means joining the upper part of the fluid container for conducting away the gas, said means including pipe connections and a union joining them, and means including a pet cock enabling the relief of the gas 100 pressure on the inside of the fluid container so that the union may be unscrewed.

3. A gas generator, comprising a chemical container, a fluid container, means for periodically dropping the fluid upon a chemical 110 in the chemical container to generate gas, means joining the upper part of the fluid

container for conducting away the gas, said means including pipe connections and a union joining them, means including a pet cock enabling the relief of the gas pressure 5 on the inside of the fluid container so that the union may be unscrewed, and means situated between and communicating with the gas spaces of both containers for equalizing the gas pressures thus preventing impedance to the dropping of the fluid, said 10 means including an equalizing pipe.

4. A gas generator, comprising a chemical container with a threaded rim, a fluid container with a threaded part, a combined coupling and partition joining the two containers, a dome having a duct and fluid opening 15 formed in the coupling, a valve regulating

the size of the opening to control the dropping of fluid from the upper to the lower container, an equalizing pipe fixed in the 20 partition and communicating with the gas space in the chemical container and the gas space in the fluid container above the fluid, to equalize the gas pressures and prevent the impedance of the dropping of the fluid 25 by excessive gas pressure in the chemical container, a gas connection having a bore with a flared entrance to facilitate the pouring in of fluid, a gas pipe joining the connection, a union making the connection between 30 the two, and a pet cock for the relief of gas inside of the fluid container to enable the unscrewing of the union.

LESLIE M. N. WISE.
